US00D638854S

(12) **United States Design Patent**
Andre et al.

(10) **Patent No.:** US D638,854 S
(45) **Date of Patent:** ** May 31, 2011

(54) **MEDIA DEVICE**

(75) Inventors: **Bartley K. Andre**, Menlo Park, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Steve Jobs**, Palo Alto, CA (US); **Duncan Robert Kerr**, San Francisco, CA (US); **Shin Nishibori**, Portola Valley, CA (US); **Matthew Dean Rohrbach**, San Francisco, CA (US); **Douglas B. Satzger**, Menlo Park, CA (US); **Calvin Q. Seid**, Palo Alto, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/379,225**

(22) Filed: **Nov. 16, 2010**

Related U.S. Application Data

(60) Continuation of application No. 29/361,026, filed on May 4, 2010, now Pat. No. Des. 627,367, which is a continuation of application No. 29/343,120, filed on Sep. 8, 2009, now Pat. No. Des. 616,899, which is a division of application No. 29/334,452, filed on Mar. 26, 2009, now Pat. No. Des. 601,172, which is a division of application No. 29/296,899, filed on Oct. 30, 2007, now Pat. No. Des. 589,530, which is a continuation of application No. 29/265,521, filed on Sep. 1, 2006, now Pat. No. Des. 560,228.

CLAIM

The ornamental design for a media device, as shown and described.

DESCRIPTION

FIG. 1 is a front perspective view of a media device showing our new design.

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The dashed broken lines in the Figures show portions of the media device which form no part of the claimed design. The dot-dash broken lines in the Figures show unclaimed boundary lines and form no part of the claimed design.

1 Claim, 4 Drawing Sheets
